MULTIPLE SECTION ANTENNA

George H. Brown, Haddonfield, N. J., assignor to
 Radio Corporation of America a corporation of
 Delaware

Application November 22, 1941, Serial No. 420,041

10 Claims. (Cl. 250—33)

This invention relates to multiple section antennas and particularly to an improved antenna in which the outer conductors, consisting of a plurality of sections of concentric lines, are used as radiators and in which inner portions of the concentric lines are used as phasing reactors and a mechanical support.

The Franklin antenna is one in which several radiating sections are connected by non-radiating phasing sections. The radiating sections are conventional conductors and the phasing sections are folded conductors. In practice it is difficult to develop folded sections which do not radiate and which offer the proper impedance to the applied currents. Since sectional antennas of the single conductor type are usually not self-supporting, it becomes necessary to provide a support together with means for insulating the several sections.

One of the objects of the present invention is to provide an improved multiple section antenna. Another object is to provide an improved multiple section self-supporting antenna. Another object is to provide improved means whereby a multiple section antenna may be adjusted to produce a predetermined radiation pattern. An additional object is to provide means whereby a plurality of sections of concentric lines are connected so that applied currents establish radiation fields of predominantly the same phase from the several sections.

The invention will be described by referring to the accompanying drawing in which Fig. 1 is an elevational view of one embodiment of the invention; Fig. 2 is a graph representing the field pattern of the antenna of Fig. 1; Fig. 3 is an elevational view of a vertical antenna arranged in accordance with the invention; and Fig. 4 is a sectional view along the line 4—4 of Fig. 1.

Referring to Fig. 1, on a grounded plate or screen 1 four sections of concentric transmission line are arranged as follows: The inner conductor 3 of the four sections is a continuous conductor on which are located four pairs of shorting plugs 5, 5', 7, 7', 9, 9' and 11, 11'. Each pair of shorting plugs support one of the four sections of the outer conductors 13, 15, 17, 19 of the transmission line. By way of example, the end conductors 13 and 19 are each $\frac{1}{4}$ of the operating wave length long. The central conductors 15 and 17 are each $\frac{1}{8}$ of the operating wave length long. The adjacent edges of the outer conductors are separated by a small air gap. The centrally located outer conductors 15 and 17 are supported by metal elements 21 and 23. One of 55

the supporting elements 23 may act as a portion of the concentric feed line 25 which is connected to the transmitter 27 or other radio device. The end conductors 13 and 19 are supported by metal elements 29, 31 which are located at voltage nodes.

The shorting plugs 5 and 11 are located near the ends of the end sections 13 and 19. The electrical location of these plugs is not important as 10 they serve only as supports for the outer conductors 13 and 19. The adjacent shorting plugs 5' and 7', and 9' and 11' are so spaced with respect to each other that they, in conjunction with the intervening concentric line conductors, constitute an inductive reactance so that the currents traversing the inside portion of the outer conductors 13, 15 and 17, 19 and the inner conductor 3 between the plugs 5', 7' and 9', 11', are phased as hereinafter described. The shorting plugs 7 and 9 at the central portion of the antenna are spaced so that the antenna impedance matches the impedance of the concentric feed line 25.

The operation of the antenna is as follows: The currents applied to the central sections 15, 25 17 are distributed over the outside portions of the central sections as shown in the graph above the antenna of Fig. 1. Since the central sections have a total length of $\frac{3}{4}$ of a wave at the operating frequency it follows that the current distribution will be a half wave 33 at the center of the antenna followed by oppositely polarized $\frac{1}{8}$ waves 35, 37 at the remote ends of the central sections. The applied currents then flow along the inner walls of the outer conductors 15, 17; 30 along the shorting plugs 7', 9'; along the inner conductors to the shorting plugs 5' and 11'; along the plugs 5' and 11'; and along the inner walls of the outer conductors 13 and 19. The current distribution on the end sections 13 and 19 starts 35 with $\frac{1}{8}$ wave distribution of the same phase as the $\frac{1}{8}$ wave distribution on the neighboring conductors 15 and 17 and then ends with half wave distribution as indicated by the curves 39, 41, respectively. The distribution of currents flowing within the inner surfaces of the concentric lines, as distinguished from the outer or radiating surfaces, is not shown because these surfaces do not radiate and therefore do not contribute to the response or radiation field established about 40 the antenna.

The main radiation is established by the currents of half wave distribution 33, 39, 41. The out of phase components corresponding to the $\frac{1}{8}$ wave 35, 37, 43, 45 distribution, theoretically detract from the main radiation. This has not

proven detrimental because in many cases the out of phase components tend to confine the field to useful regions. For described lengths and spacings of shorting plugs, the field pattern shown in Fig. 2 was obtained. The main single lobe was resolved into two lobes by changing the spacing of the shorting plugs 5', 7' and 9', 11'. The field pattern may be varied over a wide range by varying the lengths of the radiating portions and the reactance of the non-radiating portions.

The invention may be applied to an antenna for radiating vertically polarized waves. Such an arrangement is shown in Fig. 3 in which the inner conductor 51 is the support for the antenna. The inner conductor may be grounded and may be supplied with ground rods 53. Shorting plugs 55, 57, 57', 59, 59', 61, 61' and 63 are attached to the inner conductor. The shorting plugs serve two functions: the first is to support the outer conductors 65, 67, 69 and 71; the second is to provide non-radiating reactance sections of the type previously described by reference to Fig. 1. The first outer conductor section 65 is connected to the inner member of a concentric fed line 73 which is connected to the transmitter 75, or receiver if the antenna is used for reception. The outer member of the fed line is connected to ground and to the inner conductor 51 of the antenna.

The spacing of the lowest plug 55 is adjusted to match the antenna impedance to the fed line impedance. The spacings of the adjacent pairs of shorting plugs 57—57', 59—59', and 61—61' are adjusted to obtain the desired reactance between the adjacent radiating sections. The lowest section 65 is made $\frac{3}{8}$ of a wave length of the applied current. The central radiating sections 67, and 69 are each $\frac{3}{4}$ of a wave length. The highest section is made $\frac{5}{8}$ of a wave length. The current distribution of the several radiating sections is illustrated by a graph 77 which is a part of Fig. 3. The field pattern of the antenna will be circular. In an antenna of this type the out of phase components do not necessarily indicate a loss because properly related to the in phase components, they tend to suppress sky wave radiation and to confine the main radiation to the useful path parallel to the earth's surface.

While the invention has been described as composed of sections of concentric line it should be understood that the outer conductors need not be solid but may be fabricated from wires, or screens. The vertical antenna may be provided with reflectors or directors, if a directive pattern is desired. Moreover, such reflectors or directors may be rotated or oscillated to produce a rotating or oscillating pattern.

I claim as my invention:

1. A multisection antenna including an inner conductor, a plurality of separated outer conductors, and conductive means attached to said inner conductor for supporting said outer conductors and spaced to form reactive sections connecting said outer conductors in series.

2. A multisection antenna including an inner conductor, a plurality of separated and linearly arranged outer conductors, shorting plugs attached to said inner conductor and located in pairs connected respectively to adjacent outer conductors to form reactance sections therebetween effectively connecting said outer conductors in series, and means for effectively connecting a radio device to said antenna.

tors in series, and means for effectively connecting a radio device to said antenna.

3. A multisection antenna including an inner conductor, a plurality of adjacent outer conductors, conductive means attached to said inner conductor for supporting said adjacent outer conductors and spaced to form reactive sections connecting said adjacent outer conductors in series, and means for connecting a radio device to said antenna.

4. A multisection antenna including an inner nonradiating conductor, a plurality of adjacent radiating outer conductors arranged in a line, shorting members attached to said inner and outer conductors and forming reactive sections connecting said adjacent radiating conductors in series so that the main radiation from said conductors is in the same phase, and means for connecting a radio device between the adjacent ends of two of said outer conductors.

5. A multisection antenna including an inner nonradiating conductor, a plurality of adjacent radiating outer conductors, shorting members attached to said inner and outer conductors and forming reactive sections connecting said adjacent radiating conductors in series so that the main radiation from said conductors is in the same phase, means for connecting a radio device between the adjacent ends of two of said outer conductors, and additional shorting members spaced with respect to said connecting means for adjusting the input impedance of said antenna.

6. A multisection antenna including an inner conductor, a plurality of adjacent outer conductors, conductive members attached to said inner conductor for supporting said adjacent outer conductors and spaced to form reactive sections connecting said adjacent outer conductors in series, and means for connecting a radio device between said inner conductor and one of said outer conductors.

7. A multisection antenna including an inner conductor, a plurality of adjacent outer conductors each of a length not less than a quarter of the operating wave length, conductive members attached to said inner conductor for supporting said adjacent outer conductors to form reactance sections connecting said adjacent outer conductors in series, and means for applying radio frequency currents to the adjacent ends of two of said outer conductors so that the current distribution corresponds to a plurality of half waves of the same phase.

8. A device according to claim 7 including means for adjusting the impedance between said adjacent ends.

9. A multisection antenna including an inner conductor, a plurality of outer conductors arranged in a line and each of a length not less than a quarter of the operating wave length, conductive members attached to said inner conductor and to said outer conductors to form reactance sections connecting adjacent outer conductors in series, and connections for applying radio frequency currents to the adjacent ends of a pair of said outer conductors.

10. An antenna according to claim 7 including a ground screen and conductive means for supporting said outer sections in parallel spaced relation to said ground screen.

GEORGE H. BROWN.
